MULTIPLE BIN DISPENSING RACK FOR CIGARETTE PACKAGES

Simon Heselov, Youngstown, Ohio

Application January 14, 1958, Serial No. 49,250

Term of patent 14 years

(Cl. D52—2)

The figure is a perspective view of a multiple bin dispensing rack for cigarette packages, showing my new design.

The back and bottom are substantially plain. The side, not shown, is a mirror image of the side illustrated.

I claim:

The ornamental design for a multiple bin dispensing rack for cigarette packages, as shown and described.
